(57) **CLAIM**

The ornamental design for the fishing hook and line storage holder, as shown and described.

DESCRIPTION

FIG. 1 is a perspective view of the fishing hook and line storage holder of the present invention.

FIG. 2 is a top view of the fishing hook and line storage holder of the present invention.

FIG. 3 is a bottom view of the fishing hook and line storage holder of the present invention.

FIG. 4 is an elevation view of the fishing hook and line storage holder of the present invention.

FIG. 5 is an opposite elevation view of the fishing hook and line storage holder of the present invention.

FIG. 6 is a front view of the fishing hook and line storage holder of the present invention; and,

FIG. 7 is a rear view of the fishing hook and line storage holder of the present invention.

The broken lines showing a fishing hook and fishing line are included for the purpose of illustrating use and environment and forms no part of the claimed design.
